UNITED STATES PATENT OFFICE.

HARRY FRANK, OF BROOKLYN, NEW YORK.

BURGLAR PROTECTION.

Application filed November 10, 1926. Serial No. 147,451.

This invention relates to means for protecting business establishments against a successful robbery or hold up during business hours when customers are frequenting the establishment and at which time undesirable persons, in many instances, mingle with the customers and suddenly stage a hold up either of a customer or of one or more of the employees of the establishment. 5 It is not uncommon in business establishments which handle large sums of money or quantities of jewelry, or other valuables to hire watchmen or special officers who are stationed on the floor of the establishment 10 as a protection against robbery, but, in numerous instances in the past, prospective hold up men have shot or intimidated the special officers as an initial step in the operation of effecting a robbery. 15 The object of the present invention is to provide simple and thoroughly efficient means whereby a special officer may be stationed in a position which will render him immune to attack and will enable him, 20 nevertheless, to command a full view of the establishment whereby he is able to attack the prospective hold up man, in the event of an emergency, from a place of security. 25 Devices have heretofore been suggested to 30 provide a place of security for a special officer, but such structures with the exception of the construction disclosed in my prior Patent No. 1,567,728, issued December 30, 1925, have been built into and form a part 35 of the furniture or fixtures of the bank or other business establishment in which they are installed. They are highly expensive to 40 to install and, in the majority of cases, provide relatively little protection. The construction of the present invention, in contradistinction, is adapted to be built as a 45 complete unit and transported to and set up in the establishment without necessitating permanent attachment thereto. The device 50 may be moved from one position to another in the establishment as may be desirable 55 and constitutes an improvement upon the construction of my prior patent. The present invention is more particularly 50 directed to structural features, among which may be mentioned novel and efficient means for properly ventilating the enclosure in which the special officer is adapted to be stationed. This enclosure is of bullet proof 55 material and unless it is properly ventilated the person housed therein will be subjected to considerable discomfort. The present invention provides for a thorough ventilation of the enclosure. Another feature of the invention consists 60 in the employment of a novel and efficient loop hole construction adapted to normally occupy a closed position, but so constituted that it may be readily opened to permit the barrel of a weapon to be thrust therethrough 65 for the purpose of firing upon intruders. The loop hole construction is such that it cannot be manipulated from the exterior of the enclosure, but may be manually operated with ease from the interior thereof. It automatically operates to provide no greater 70 opening than is necessary to permit the barrel of a gun or pistol to protrude therethrough and upon the withdrawal of the weapon it automatically closes. 75 The enclosure is also provided with bullet proof sight openings which are glazed with bullet proof glass, so that the occupant can readily see what is transpiring exteriorly of the closure without necessitating the opening 80 of windows, the doors or other openings through which tear bombs or similar articles of attack might be projected into the enclosure. 85 The construction of the device of this invention is simple, economical and thoroughly efficient for the carrying out of its intended purposes and constitutes a marked improvement on everything that has gone before. 90 Features of the invention, other than those adverted to, will be apparent from the hereinafter detailed description and claims, when read in conjunction with the accompanying drawings. 95 The accompanying drawings illustrate one practical embodiment of the invention, but the construction therein shown is to be understood as illustrative, only, and not as defining the limits of the invention. 100 Figure 1 is a perspective view of the device of this invention. 105 Figure 2 is a vertical section through the enclosure on the line 2—2 of Figure 1. Figure 3 is an enlarged detail section illustrating a portion of the construction which permits of proper ventilation. 110 Figure 4 is a fragmental elevation of the side wall of the enclosure as viewed from the inside thereof and showing the loop hole and window construction. 115 Figure 5 is a section on the line 5—5 of Figure 4.

Figure 6 is a section on the line 6—6 of Figure 4; and,

Figure 7 is a section on the line 7—7 of Figure 2.

Referring to the drawings, 1 designates the enclosure which, as shown in Figure 1, is preferably mounted upon a suitable tower or other supports 2 which may be of any desired height, so that the enclosure may be supported at any elevation above the floor as the construction of the business establishment or other circumstances may require. It is within the purview of this invention to support the enclosure at a relatively high elevation and out of the reach of persons on the floor, although said enclosure may also be mounted substantially at the floor level, without departing from the invention. In practice, however, the mounting of the closure at a high elevation is preferred.

The enclosure is provided with four walls 3, 4, 5 and 6, a floor 7, and a suitable roof 8, the latter of which is shown as sloping although it may be made flat or otherwise without departing from the invention. The side walls, the roof and the floor are constructed of bullet proof steel mounted upon a suitable framework 9 which serves to reinforce the enclosure and lend stability and rigidity thereto.

Access may be had to the enclosure through a doorway 10, normally closed by a door 11 preferably mounted to slide on a track 12 positioned interiorly of the enclosure. The door is provided with a lock 13 whereby it may be locked from either the inside or the outside.

Positioned at suitable and convenient places in the side walls of the enclosure are openings 14 sufficiently large to permit a pistol or gun barrel to be thrust therethrough. Any number of these holes may be provided and they may be positioned in any desired places in any one or more of the side walls. In Figure 1, no such opening is shown in the wall 3, since in the particular construction shown the wall 3 is intended to be positioned relatively close to one of the walls of the room in which the enclosure is to be installed and there would be no advantage in having a hole in the wall 3 in such an arrangement. However, I do not limit myself in this regard but wish it understood that these holes 14 may be provided in any desired position and in any desired number.

Interiorly of each hole and juxtaposed therewith is a slide 15 mounted to reciprocate between guides 16. As shown in Figure 4, the slide has an imperforate part adapted to normally close the associated opening 14 and also is provided with an opening 14^a of substantially the same size and shape of the opening 14. An operating handle 17 is secured to the slide and operates in a guide 18 and a spring 19 is positioned

between the slide and the guide 18 to normally force the slide into a closed position. In order to permit a gun barrel to be projected through the opening 14, it is only necessary for a person within the enclosure to withdraw the slide against the tension of the spring 19 until the holes 14 and 14^a register. This operation is facilitated by providing a finger grip 20 adjacent to the handle 17, so that the fingers may be engaged with the grip 20 while the thumb is utilized to move the slide as stated. After the openings have been moved into registration, a pistol barrel may be thrust through the opening and the slide may then be released, so as to partially close against the gun barrel to leave the smallest possible opening. By virtue of the spring pressure, however, the gun may be swung into different angular degrees with reference to the side wall of the enclosure and may be properly aimed. When the gun is withdrawn the spring will force the slide into closed position.

The loop hole construction which I have described is unusually simple. It is economical to manufacture and is thoroughly efficient in use. It is a marked contrast to the complicated loop hole constructions of the prior art. It can not be inadvertently left open and is automatically closed after use.

In order to permit the occupant of the enclosure to keep watch on activities exterior thereof, I preferably provide over each loop hole a window 21. This window is hinged at 22 at the inside of the enclosure and it is normally locked shut by a spring lock 23. It is glazed with bullet proof glass 24, so held in position as shown in Figure 5, that the glass can not be removed from the exterior of the enclosure. The windows may be opened if desired for any purpose, but when closed will automatically be locked in closed position by the spring lock 23.

Some light will be admitted into the enclosure through the openings to which I have referred, but inasmuch as this light will necessarily be limited, I preferably provide a skylight 25 in the roof of the enclosure. This skylight embodies a plate of bullet proof glass 26 held in place by angles 27 secured to the roof, as shown in Figure 2. Ample light is admitted through this skylight to permit the occupant of the enclosure to properly function therein.

In a relatively tight enclosure of the character to which I have referred, the question of ventilation is an important one, particularly in summer when the heat within the enclosure may be uncomfortable to the occupant. To permit of proper ventilation, I provide each of the side walls 4 and 5 directly beneath the eaves of the roof with longitudinal slots 28 which preferably extend the full width of each side wall and directly within the enclosure I mount on the

5 roof angle baffles 29, as shown in Figure 2 and detailed in Figure 3. These angle baffles are so shaped, that they will preclude the passage of a bullet through the opening 28 and into the interior of the enclosure in any manner as would cause injury to the occupant. The free edges of the baffles are, however, spaced from the side walls 4 and 5, as shown in Figure 3, sufficiently to permit 10 the entrance and exit of air through the openings 28.

15 Adjacent the floor of the enclosure and in two or more of the side walls are formed slots covered by baffles 30 which preferably incline in an upward direction, as shown in Fig. 2, so that if a bullet is fired in an upward direction against these baffles, it will be deflected and will not enter the enclosure. When the enclosure is built for use in an 20 elevated position, the baffles 30 are as shown in Figure 2, but if it is constructed for use at or adjacent the floor of a business establishment, the baffles are preferably inclined in a downward direction so that bullets 25 fired in the latter direction will not enter the openings between the baffles.

30 Considerable air may circulate through the openings with which the baffles 30 are associated. In order to provide more circulation the floor 7 may be provided with one or more mushroom ventilators 31 which will permit the circulation of air in the enclosure while precluding the passage of bolts into the interior of the enclosure.

35 Experience has shown that when an enclosure is provided with the ventilating means to which I have referred, adequate ventilation is provided if the enclosure is adapted for use directly above the floor of 40 a building, the mushroom ventilators are of course omitted, but in all cases where the enclosure is placed above the floor these ventilators are preferably employed.

45 It will of course be understood that in practice the interior is fitted for the convenience and comfort of the occupant and a telephone connection thereto may be provided, so that in the event of an emergency the occupant can summon police aid. I have 50 not shown these details in the drawings as their use in this connection will be apparent.

Having thus fully described the invention, what I claim as new and desire to secure by Letters Patent is:

55 1. An assembly of the character described embodying an enclosure having bullet proof

walls provided with openings through which a weapon may be projected, a slide mounted for sliding movement on the interior of the enclosure adjacent each opening and provided with an opening adapted to be moved into registration with the opening of the enclosure, automatic means for normally moving the slide into a position wherein the openings of the enclosure and slide are out 60 of registration, and a transparent bullet proof window positioned above each opening of the enclosure whereby the persons to be fired upon may be observed without exposing the occupant of the enclosure to 65 attack.

2. An assembly of the character described embodying an enclosure having walls of bullet proof material and at least one of which walls is provided with an opening 75 through which the barrel of a weapon may be projected, a slide positioned interiorly of said wall and also provided with an opening, automatic means for impelling the slide into a position wherein the openings are out of registration, means for retracting the slide to move the openings into registration, and a transparent bullet proof window positioned adjacent the opening and through which a person positioned within 80 the opening can observe persons to be fired upon without exposing the person within the enclosure to attack.

3. An assembly of the character described embodying an enclosure having walls of 90 bullet proof material and at least one of which walls is provided with an opening through which the barrel of a weapon may be projected, a slide positioned interiorly of said wall and also provided with an opening, automatic means for impelling the slide into a position wherein the openings are out of registration, means for retracting the slide to move the openings into registration, a transparent bullet proof window positioned adjacent the opening and through 95 which a person positioned within the opening can observe persons to be fired upon without exposing the person within the enclosure to attack, and means for locking the window from the interior of the enclosure to preclude unlocking of the window from the exterior thereof.

In testimony whereof I have signed the foregoing specification.

HARRY FRANK.
